LOOSE LEAF BINDER

Paul O. Unger, Glen Ellyn, and Fred D. Wedge,
Lombard, Ill., assignors to Wilson-Jones Com-
pany, Chicago, Ill., a corporation of Massa-
chusetts

Application November 26, 1934, Serial No. 754,786

2 Claims. (C.I. 129—1)

This invention relates to a loose leaf binder, and more particularly to an arch binder in which folded sheets or groups of sheets are retained by means of wires positioned between the folded edges of the sheets and the underside of a plurality of arches. This type of binder is exemplified by the patents to McCleary Nos. 1,843,575 and 1,843,608, both issued February 2, 1932.

Binders of this type have proved to be very successful in connection with pamphlets or groups of folded sheets but the field of use therefor has been limited because the binder is not adapted to receive single unfolded sheets. It is often desirable to insert single unfolded index or correction sheets in a binder containing a plurality of pamphlets or groups of folded sheets, but heretofore no binder of this type has been available in which such insertions can be made without necessitating so much effort as to make the binder impractical for the intended purpose.

It is an object of this invention to provide a loose leaf binder adapted to retain a plurality of sheets either folded or unfolded. It is a further object of this invention to provide a loose leaf binder particularly adapted to retain groups of folded sheets with means for permitting rapid and easy insertion of single unfolded sheets. It is a further object of this invention to provide a binder of this type with a convenient accessible magazine for carrying extra sheet retaining wires that will not interfere with the normal operation of the binder, and will not detract from the appearance of the binder. Other objects of this invention will become apparent upon reading the following description taken in conjunction with the accompanying drawing, in which

Figure 1 is a perspective view of a loose leaf binder embodying the invention with parts broken away to facilitate illustration of the structure.

Figure 2 is a fragmentary view, partly in plan and partly in section, of the binder shown in Figure 1; and

Figure 3 is a cross sectional view taken along the line III—III of Figure 2.

In the drawing, the reference numerals 2, 3 and 4 respectively indicate a back member and a pair of cover members integral with the back member or secured to opposite edges thereof. A metal spring back 5 is secured to the back member 2 in any conventional manner. Two toggle plates 6 are positioned in the spring back in side by side relation with their outer longitudinal edges restrained from outward movement by the upturned edges 7 of the spring back.

Each toggle plate 6 has secured thereto a plu-

rality of prong members 8. The prong members meet at their outer ends when the toggle plates are in closed position to form arches. A cover plate 9 is provided with downwardly bent edges 10 adapted to embrace the edges 7 of the spring back. The cover plate 9 is notched along its longitudinal edges, as indicated at 11, to allow the prong members 8 to project therethrough. The arc of the prong members has substantially the same axis and is parallel to that of the cover plate when in closed position.

Each folded sheet 12 is provided with a plurality of notches 13 adapted to straddle the arches 8. A wire 14 is positioned inside the folded edge of the sheet and under the arches to 15 retain the folded sheet in the binder just as in conventional binders of this type. Unfolded sheets 15 are punched and inserted on the arches just as in the case of conventional ring books. Of course, the folded sheets with the wires positioned adjacent the folded edge may also be inserted on the arches when they are in open position.

A pair of triggers 16 is provided at opposite ends of the metal to move the toggle plates to open and closed position. The specific structure of the trigger constitutes the subject matter of a separate application, Serial No. 750,446 filed October 29, 1934 in the name of Paul O. Unger, which is issued as Patent No. 2,056,812 on October 6, 1936. Accordingly, it is deemed to be unnecessary to describe the trigger structure in detail in the present application. Any trigger capable of moving the toggle plates 6 to open and closed position may be used in the present structure. However, the trigger must extend above the cover plate at least as much as the arch members, in order to prevent the accidental displacement of the sheet retaining wires. The preferred embodiment of our invention is shown with a trigger at each end. However, it is obvious that a single trigger may be substituted, and one end of the metal may be provided with any conventional closure that extends above the cover plate enough to serve as a stop member for the ends of the sheet retaining wires.

A tubular member 17 is secured to the cover member 4 near its outer edge to provide a magazine for carrying extra sheet retaining wires 14. The magazine may be made of any suitable material. One end of the magazine is threaded, as indicated at 18, Figure 2, and is provided with a similarly threaded closure member 19. The outer end 20 of the closure member 19 is preferably knurled to facilitate turning thereof. Al-

5 though the magazine may be secured to the cover member 4 in any desired manner, it is preferred to enclose it in a strip of fabric 21 and to secure the ends 22 of the fabric strip under the lining member 23. If the cover member is not lined, the fabric strip may be sewed or cemented directly to the cover member. It will readily be seen from an inspection of Figure 3, that the magazine carrying the spare wires cannot interfere with the normal operation of the binder.

10 15 Although we have described a preferred embodiment of our invention in detail, it will be understood that the description thereof is illustrative, rather than restrictive, as many details may be modified or changed without departing from the spirit or scope of our invention. Accordingly, we do not desire to be restricted to the exact construction described, except as limited by the appended claims.

20 We claim:

1. In a loose leaf binder, a plurality of sectional arch members, a plurality of folded sheets notched at their folded edges to straddle said arch members, a plurality of wires positioned within the folded edges of said sheets and under said arches to retain said folded sheets in the binder, and means at each end of said binder to prevent accidental longitudinal displacement of said wires, said last mentioned means being operable to open said sectional arch members.

2. In a loose leaf binder, a plurality of sectional arch members, a plurality of wires cooperating with said arch members to retain folded sheets in the binder, and a pair of triggers at opposite ends of the binder, said triggers being adapted to prevent accidental longitudinal displacement of said wires and operable to open said sectional arch members.
